UNITED STATES PATENT OFFICE.

CARL HARTMANN, OF SAN FRANCISCO, CALIFORNIA, ASSIGNOR OF ONE-HALF TO
JOHN E. ANDERSON, OF SAN FRANCISCO, CALIFORNIA.

AUTOMATIC VALVE.

Application filed April 22, 1926. Serial No. 103,853.

My invention relates to improvements in automatic control valves for water heaters and the like, wherein the fluid pressure of water circulated through the heater is arranged to automatically control the supply of fuel to the heater burner whereby the supply of fuel may be kept proportional to the flow of water to be heated.

The primary object of my invention is to provide an improved valve for automatically regulating the flow of fuel to the burner of a water heater to conform to the flow of water to be heated.

Another object is to provide an improved device which is simple and positive in its action and which will efficiently restrict the flow of fuel to the quantity required for the quantity of water to be heated, and thereby effect economy in fuel consumption.

A further object is to provide an improved device of the character described, which may be easily and accurately adjusted to obtain a desired ratio between the flow of water and fuel to a heater, whereby the degree of heat and the gas consumption may be regulated.

Another object to provide an improved valve which is entirely automatic in its action and which is of a strong rugged construction free from delicate parts.

A still further object is to provide an improved valve construction which may be economically manufactured, assembled and installed.

I accomplish these and other objects by means of the improved device disclosed in the drawings forming a part of the present specification, wherein like characters of reference are used to designate similar parts throughout said specification and drawings and in which,

Fig. 1 is a broken side elevation of a water heater showing my improved valve connected therewith.

Fig. 2 is a plan view of the valve drawn upon a somewhat larger scale.

Fig. 3 is a longitudinal vertical section of the valve showing the internal construction thereof.

Fig. 4 is a broken horizontal section through the valve fitting showing the construction and operation of the fuel valve therein.

Referring to the drawings, the numeral 1 is used to designate in general a water heater

of the type wherein water is circulated through suitable coils 2 wherein it is heated by a suitable burner 3 consuming gas or other fuel; the water being heated while flowing through the coils 2 to the point of discharge.

The present invention is directed to an improved valve for automatically turning and regulating the supply of fuel to meet the requirement for the quantity of water being drawn through the heater at any particular moment. My improved valve consists of a fuel fitting 4 having an inlet 6 arranged to be connected to a source of fuel supply and an outlet 7 arranged to be connected to the heater through a suitable shut-off valve 8 and tubular connection 9 connected to the burner 3. The fitting 4 is provided with a partition 11 having a valve seat 12 formed therein to communicate between the inlet and outlet portions of the fitting. A valve 13 provided with a stem 14 extending outwardly through a side of the fitting 4 is arranged to engage the valve seat 12 to control the flow of fuel therethrough.

A water fitting 16 is arranged to be connected between a source of water supply and the coils 2 of the heater, said fitting consisting of a cylindrical body portion within which is slidably mounted a piston 17. Water is introduced into the cylindrical body through an inlet connection 18 upon the outer side of the piston 17. An outlet connection 19 is connected into the fitting 16 in such manner as to open in back of the piston 17, said outlet connection 19 being connected in any suitable manner to the coils 2 of the heater. A passage 21 tapering towards the forward end of the piston 17 communicates between the forward portion of the cylinder and the outlet whereby water may flow past the piston from the inlet to the outlet.

The piston is provided with a suitable stem 22 extending outwardly through the back of the fitting 16, a suitable stuffing gland 23 being provided to prevent the leakage of water past said stem.

The fuel fitting 4 and water fitting 16 are connected by means of a tubular member 24 threaded onto extensions and formed upon the fittings 4 and 16 respectively. The tubular member 24 is arranged to secure the fittings together with the stems 14 and 22 in axial alignment. The sides of the tubular

member 24 have openings 26 formed in opposite sides thereof for a purpose herein-after more fully explained.

An adjusting nut 27 is threaded unto the 5 end of one of the stems, preferably the valve stem 14, said nut being provided with flanges 28 and arranged to engage the adjacent end of the opposite stem whereby a longitudinal movement of one stem will be imparted 10 to the other. The nut 27 is made relatively long to permit adjustment in a manner herein-after more fully described.

A spring 30 is mounted around the valve stem 14 and compressed against the fitting 15 4 by means of an adjusting nut 29 threaded onto said stem 14. The nut 29 is provided with a flange 31 whereby the nut may be turned to adjust the degree of pressure exerted by the spring 30 and the degree of 20 resistance offered by said spring to a longitudinal movement of the valve 13, said spring being arranged to normally hold the valve 13 seated upon the valve seat 12.

A pilot light is mounted adjacent to the 25 shut-off valve 8 and extended to a point near the burner 3, fuel being supplied to said pilot light through a tubular connection 33 connected to the inlet side of the fuel fitting 4. A suitable cock 34 is connected between 30 the tubular member 33 and the pilot light and arranged to be manually operated by means of a suitable lever 36 for controlling the supply of fuel to the pilot light. The lever 36 is preferably arranged to extend 35 across the course of movement of a lever 37 provided upon the shut-off valve 8, as shown in Fig. 2, whereby said shut-off valve cannot be opened when the pilot light is shut off.

In operation my improved automatic 40 valve is as follows: The piston 17 is adjusted longitudinally by means of the adjusting nut 27 until only a slight opening through the tapered passage 21 is afforded when the valve 13 is seated upon the valve seat 12, thus permitting the normal pressure 45 under which the water is delivered from its source to be equalized upon opposite sides of the piston. When now it is desired to draw heated water at a point of delivery, 50 the turning on of the water at said point of delivery will cause a reduction of pressure upon the outlet side of the piston. The water upon the inlet side of the piston, being 55 under normal pressure will be forced through the passage 21 and will be conducted through the coils 2 of the heater wherein it is heated before delivery. The difference in pressure upon opposite sides of the piston will cause said piston to be moved 60 inwardly against the pressure of the spring 28 until a balance is reached and the opening through the tapered end of the passage 21 past the piston is made sufficiently great to accommodate the flow of water being 65 withdrawn at this point of delivery.

The inward movement of the piston 17 caused by the drawing of water through the water fitting 16 causes the valve 13 to be moved a corresponding amount, thereby opening the valve and permitting a flow of 70 fuel therethrough to the burner 3 where it is ignited by the pilot light and caused to heat the water passing through the coils 2 in the well known manner. The degree to which the valve is opened is proportional to the 75 movement of the piston which in turn is proportional to the quantity of water being used. Thus if only a slight amount of water is being drawn through the heater, the piston will be moved only a very little and the 80 fuel valve will be opened only slightly, thus producing only a low flame sufficient to heat the small quantity of water being used. Should the amount of water drawn through the heater be increased, the piston will be 85 moved slightly farther inwardly and the fuel valve will be opened correspondingly wider whereby fuel sufficient to heat the increased amount of water may be delivered to the 90 burner.

The degree to which the fuel valve is 95 opened for a stated flow of water through the water fitting 16 is regulated in two ways: First, by adjusting the pressure exerted by the spring 28 and against which the piston 17 and valve 13 must be moved, and second, by adjusting the amount of the tapered passage 21 which is opened when the valve and piston are in normal valve closing position. These adjustments are obtained by advancing or receding the adjusting nuts 27 and 29 along the threaded stem 14. By increasing the pressure exerted by the spring 28, the 100 degree of movement resulting from the flow of any stated quantity of water through the water fitting 16 will be decreased, and by decreasing the pressure, the amount of valve opening will be increased. At the same time, an increase in the normal opening through the passage 21 past the piston 17 will reduce 105 the amount of movement of the piston to accommodate a stated flow of water, and a decrease in said normal opening will cause an increase in the degree of movement. In this manner the valve may be easily and accurately adjusted to cause the water to be heated to a desired degree.

This accurate control of the fuel consumption effects a great economy, as the heat produced is substantially all utilized and there 110 is no waste such as caused by heating the water to a higher degree than required, or by heating a greater quantity of water than is actually being used.

The shut-off valve 8 is normally kept open 115 and the pilot light burning so that the device operates entirely automatically to heat water to the desired degree at the moment it is to be used. When it is desired to discontinue the use of the heater for any considerable 120

time, however, the shut-off valve forms a convenient means for closing the fuel supply.

While I have illustrated and described what I now consider to be the preferred construction of my invention, the device is, of course, subject to modification in numerous ways without departing from the spirit of the invention. I, therefore, do not wish to restrict myself to the specific construction illustrated and described, nor do I wish to limit the device to the particular mode of application explained, but desire to avail myself of all modifications which may fall within the scope of the appended claim.

Having thus described my invention what I claim as new and desire to secure by Letters Patent is:

A valve for water heaters and the like, comprising a fuel fitting arranged to be connected between a source of fuel supply and a burner mounted in connection with a heater; a water fitting arranged to be connected between a source of water supply and the heater; a tubular member connected between the fuel and water fittings to hold the same in rigid spaced connection, said tubular member having oppositely disposed openings in the sides thereof; a valve mounted within the fuel fitting for controlling the flow of fuel therethrough to the burner; a

piston mounted within the water fitting and arranged to be displaced by the fluid pressure of water circulated therewith; axially aligned stems connected to the valve and piston, said stems extending axially into the tubular member; an adjusting nut threaded onto one of the stems and arranged to engage the other stem whereby a displacement of the piston will automatically cause a corresponding displacement of the fuel valve to permit a flow of fuel proportional to the flow of water, said adjusting nut being accessible through the openings in the sides of the tubular member for adjusting the normal position of the piston within the water fitting; a spring mounted around the valve stem said spring being arranged to normally hold the valve and piston in valve closing position; and an adjusting member threaded onto the valve stem and arranged to regulate the pressure exerted by said spring to vary the displacement of the piston and valve resulting from a stated flow of water, said adjusting means being accessible for adjustment through the openings in the sides of the tubular member.

In witness whereof, I hereby set my signature.

CARL HARTMANN.
